TERRY FABRIC WITH PILES OF DIFFERENT COLORS

Application filed December 21, 1927. Serial No. 241,706.

This invention relates to terry fabrics wherein the piles are formed of yarns having differing characteristics and it is the general object of the invention to provide a terry fabric wherein two or more sets of different kinds of terry pile forming warps are used, all but one of the sets of warps being buried during any one pick of the loom.

Terry towels of the better class have a body formed of terry fabric throughout its length and have borders at the ends of the towel, the borders being formed with plain and terry effects to produce different designs. Whenever it has been desired to introduce color into the border in connection with the terry effects the color has usually been in the filling which is buried beneath the piles where it cannot be seen to best advantage. For instance, the pile threads might be white and the filling might alternate from white to blue, the blue appearing under the white piles in the border. The color so laid in the fabric does not present a clean cut design inasmuch as it lies under the white piles so that only a portion of the color can be seen. It is an important object of my present invention to provide a terry fabric wherein the piles will be formed of colored yarns and wherein all the color yarns except those of one color will be buried in the fabric. By this construction the pick of filling which forms the terry loops will slide along not only the ground warps but those color warps which are to be bedded into the fabric.

It has been proposed heretofore to provide terry fabrics wherein the pile warps are of different colors, but so far as I am aware it has been necessary to form piles of all the terry warps, a construction which uses up a considerable amount of terry warp which is not necessary to the figure produced. It is a further object of my present invention to form a terry fabric having a plurality of differently colored pile warps which shall be so disposed that the non-active terry warps will lie below the active terry threads which are forming the piles so that a minimum amount of terry yarn may be employed.

With these and other objects in view which will appear as the description proceeds, my

invention resides in the combination and arrangement of parts hereinafter described and set forth in the claims.

In the accompanying drawings wherein I have shown a convenient embodiment of my invention,

Fig. 1 is a perspective view showing a portion of a terry fabric made according to my present invention with the diversity of colors independent of the heights of pile,

Fig. 2 is a perspective view of another portion of a terry fabric made according to my invention wherein the change of color is accompanied by a change of height in the piles of the fabric.

Fig. 3 is a perspective view showing two ground warps and two pairs of differently colored terry pile warps interlaced with a system of filling threads, the several threads being spaced to indicate more clearly the manner in which they are related to each other,

Fig. 4 is a longitudinal vertical section through a portion of the fabric showing one set of piles in full lines and another corresponding set which would be beside the first set indicated in dotted lines.

Fig. 5 is a diagrammatic representation of the invention as applied to a terry fabric wherein all of the piles are of the same height and lie on one side of the fabric, the relation of the two differently colored systems of terry warp threads being shown, and

Fig. 6 is a view similar to Fig. 5 but with the invention applied to terry fabric wherein the piles are of different heights and lie on both sides of the fabric.

Terry pile fabrics are generally made with the use of two distinct systems of warp threads; the so-called ground warps being relatively tight and being supplied by the usual warp beam and the other system being provided by a loose terry warp beam which is given periodic advance movement to supply the yarn from which the piles or loops are formed. My invention relates more particularly to the terry warp threads and to the manner in which they are incorporated into the terry fabric. As regards certain aspects of my invention the height of the piles

is immaterial but as regards other features of the invention the height of the pile has a direct bearing on the character of yarn which forms said piles.

In all of the forms shown herein I provide ground warp threads 10 which form a plain weave with the filling shots 11. The terry warp threads are shown as of two distinctive kinds, namely, the pair indicated at 12 being of a dark color and the pair indicated at 13 being a lighter color. The two systems of warp threads will be supplied by two different warp beams one of which will be held tight while the other is supplying the warp for the terry piles. As shown in Fig. 3 the two dark threads 12 form with the shots of filling a plain weave, that is, each of said threads 12 passes over one shot of filling, under the next, over the third etc. By referring to Fig. 3 it will be seen that those portions of the threads 12 at the left have been formed into loops or piles 14 while said threads at the right hand side of the figure are woven into the fabric without forming piles as indicated at 15. The portions 15 of these threads 12 are in effect ground warps and cooperate with the threads 10 to form the body of the fabric from which the piles project. The left hand ends of the second pair of terry warps 13 are shown in Fig. 3 as not forming piles but being comparatively flat as at 16 to form ground warps similar to the portions 15 of the first set of terry warp threads. The intermediate portions of said threads 13, however, are formed as terry piles or loops 17. It will be seen by inspecting Fig. 3 that whenever piles or loops are being formed of one set of terry pile warps the other set of pile threads will be incorporated into the fabric as ground warps so that at no time are piles formed of both sets of threads. The right hand portions 18 of the second set of terry warp threads 13 as shown in Fig. 3 are non-pile forming and are disposed as are the adjacent portions of the threads 12 to provide a plain non-pile weave.

As shown in Fig. 5 the terry piles are all of the same height, two blocks of piles 14 formed of the terry warp 12 being separated by a block of piles 17 formed from the second set of terry warp threads 13. As shown in this figure the piles all lie on one side of the cloth and this result can be attained in well known manner by proper drawing and operation of the warp threads in the several harnesses which are used to control said threads.

As shown in Figs. 1 and 2 I may employ piles of two different heights, Fig. 2 showing two blocks of relatively high piles H being separated by a block of lower piles L. This feature of the variation of the height of piles is set forth in more detail in my co-pending application Serial No. 239,372. As

shown in Fig. 1 the high piles may be of two colors or formed of terry warp threads of two distinct characters, the darker portions formed of the threads 12 being separated by the lighter portions formed of warp threads 13. The various groups of differently colored piles may be formed independently of the height of the pile as shown in Fig. 1.

In Fig. 2 the blocks H of high piles are formed of terry warp drawn from the dark set of terry warp threads 12 while the block L of lower piles is formed by terry loops formed in the other set of lighter warp threads 13.

Fig. 6 shows diagrammatically the arrangement of the blocks H and L with the ground warps and shots of filling omitted, the piles in this figure corresponding to the showing set forth in Fig. 2.

I find that terry fabrics can be made according to several different weaves depending upon the tightness of binds desired between the ground work and the terry piles. While it is permissible to provide a row of terry piles for every three, four, five or six shots of filling yet I have chosen to illustrate the invention in connection with a so-called three pick terry wherein the shots of filling may be thought of as being divided into groups of three with one row of terry piles for every group. If desired, however, the groups may contain greater numbers of shots of filling. Fig. 3 shows the piles of any one color of terry warp as being formed every third shot of filling.

It is also possible to manipulate the harnesses in a variety of ways but I have shown herein for the sake of simplicity a plain weave wherein each warp thread whether ground or pile passes over one shot of filling, under the next, over the third, etc., but I do not wish to be limited to this particular arrangement of the warp threads.

It will be observed that a feature which is common to the several forms illustrated is that only one set of terry warps is active to form piles at a time, the other set being incorporated into the cloth and acting as ground warps. This is true whether the piles be of the same or of different heights, but as a matter of practical expediency where piles of different heights are employed it is preferable to have the change in the character of the terry warp threads change with the height of piles. This is due to the fact that each set of terry warp is drawn from a separate beam and the feeds of the different beams may be different with respect to each other although the amount of yarn supplied by any one terry warp beam will be constant on successive pile forming beats of the loom.

From the foregoing it will be seen that I have provided a terry fabric wherein the piles or loops are formed of a plurality of

systems of terry warp threads, all of the terry warps except one being non-pile forming and buried in the fabric when that one set is forming pile. In this way I have been able 5 to get color effects which will present solid blocks of color and at the same time effect a saving in the color terry yarn. It will further be seen that a particularly convenient arrangement is to have the terry formed of differing heights of pile wherein the changes in 10 color or character of the terry yarn coincide with the changes in the height of the pile.

Having thus described my invention it will be apparent that changes and modifications may be made therein by those skilled in 15 the art without departing from the spirit and scope of the invention and I do not wish to be limited to the details herein disclosed, but what I claim is:

20 1. In a woven terry fabric having ground warp threads extending throughout the length of the fabric interwoven with shots of filling, two sets of distinctively different looped pile forming terry warp threads, the

25 threads of each set being interwoven with the shots of filling, the looped piles in any one continuous row extending across the fabric being drawn from one set and being of a given height and looped piles extending across the

30 fabric in another row being formed of the warp threads in another set and being of a different height from the looped piles formed by the threads in the first named set of terry pile forming warp threads.

35 2. In a woven terry fabric having ground warp threads extending throughout the length of the fabric interwoven with shots of filling, two sets of terry warp threads of distinctive characters forming different

40 transverse zones longitudinally of the fabric, each set having groups of looped piles formed therein and the threads of each set being interlaced with the shots of filling, the looped piles corresponding to any one row

45 of loops extending entirely across the fabric being supplied by but one set of terry warp threads.

3. In a woven terry fabric having ground warp threads extending throughout the 50 length of the fabric interwoven with shots of filling, two sets of terry pile forming warp threads forming different transverse zones longitudinally of the fabric, the sets being distinctively different, looped piles formed

55 of the threads of one set and extending across the width of the fabric and being of a given height, and piles formed in the other set and extending across the width of the fabric and being of a different height from the piles

60 formed from the first named set.

4. In a woven terry fabric having ground warp threads extending throughout the length of the fabric interwoven with shots of filling, two sets of terry looped pile forming warp threads of distinctive characters

forming different transverse zones longitudinally of the fabric, the looped piles extending across the width of the fabric being all formed from one set of warp threads and being of a given height, and the threads of 70 the other set being incorporated into the fabric as ground threads under the piles without forming pile, said threads of the other set being formed to provide looped piles extending across the fabric of a different 75 height from the piles formed from the first set of warp threads.

In testimony whereof I have hereunto affixed my signature.

WALTER H. WAKEFIELD.
